UNITED STATES PATENT OFFICE.

JAMES W. EASTON, OF NEW YORK, N. Y.

DYNAMO-ELECTRIC MACHINE.

SPECIFICATION forming part of Letters Patent No. 290,551, dated December 18, 1883.

Application filed February 19, 1883. (No model.)

To all whom it may concern:

Be it known that I, JAMES W. EASTON, a subject of the Queen of Great Britain, residing at New York, in the county of New York 5 and State of New York, have invented certain new and useful Improvements in Dynamo-Electric Machines, of which the following is a specification, reference being had therein to the accompanying drawings, wherein—

10 Figure 1 is a longitudinal section on line x x , Fig. 2. Fig. 2 is a vertical section, partly in elevation, of an armature, commutator, and driving-shaft of a dynamo-electric machine embodying my improvements. Fig. 3 is a detail perspective. Fig. 4 is a detail modification, and Fig. 5 is an elevation, partly sectional, of my improved pole-pieces for the armatures of electric generators.

15 My invention has relation to dynamo-electric machines, and has especial reference to the formation of the armature and the pole-pieces, whereby a simple and inexpensive construction of dynamo-electric machines is provided, wherein the heating of the armatures is prevented, and the removal of the 20 armatures from the machine is effected without disarranging all the parts of the machine.

25 My invention accordingly further consists of the novel combination, construction, and arrangement of parts, as hereinafter described and claimed, having reference particularly to the provision of an armature consisting of a frame-work of veneering of wood or other suitable material, a coil of iron wire wound around 30 the periphery of said frame, a series of bobbins or helices, and a series of fans for forcing a current of air through said coils, and to the provision of pole-pieces for the armature, which are made in two parts, whereby one of which 35 may be disconnected from the other, to permit of the removal of the armature from the machine without disturbing the connections of the latter or disarranging its parts.

40 Referring to the accompanying drawings, A represents the driving-shaft of a dynamo-electric machine, designed to be mounted or have its bearings in any suitable frame. The latter is not shown in the drawings, as it forms no part of my invention. Upon said shaft is 45 placed an armature, B, and a commutator, C. The latter may be of any suitable or desired construction.

The armature B is constructed as follows: D represents a ring, of wood or other non-conductor, having side flanges, d d , and a series of perforations, d' , in its periphery. Within the central opening, d'' , of said ring are placed three or more wire rings, d' ; or the latter may be of wood or other material tacked to or formed integral with the ring D, as indicated in Fig. 4. Around the circumference of ring D, and between its flanges d d , is wound a helix of uninsulated iron wire, E. The latter is flush with the edges of the flanges d d , as shown. The iron-wire helix E serves as 55 the core for the armature, and is designed to be wound so that there will be a slight interspace between adjacent coils for the passage of air, as hereinafter explained.

55 F represent a series of helices wound transversely to the iron-wire helix E, and between the helices F are interposed hollow wooden or other blocks G G'. These blocks are so made that their inner chambers or hollow spaces g g communicate with the air-chambers D', formed 60 between the ring D and the helices F, by the interposition of the wire or wooden rings d' . The blocks G have closed upper ends, g^1 , and open bottoms g^2 , with projecting side or lip g^3 , located within the central opening of the armature, as shown. The blocks G' have closed 65 bottoms g^4 and open upper ends, g^5 . By such arrangement the armature B is provided with a series of internal air-chambers, D', inlet-openings D², and outlets D³, so that as it rotates the projecting sides g^3 of the blocks G 70 serve as fan-blades to force a current of air into the induction-openings D², thence into chambers D', thence through the perforations d' in wooden ring D, thence through the coils 75 E and F and eduction-openings D³. A current or successive currents of air are thereby forced through the armature as it rotates by means of devices attached to said armature. Such air passing around and through the coils 80 of the helices prevents undue heating of the same. The armature is therefore thoroughly ventilated and kept cool. The direction of the air-currents is indicated by the arrows in Fig. 1.

85 The armature is connected to shaft A in the 85 following manner:

90 H represents a sleeve or hub firmly secured to said shaft, and provided with three or more radial lugs, h ; or a collar may be sub-

stituted therefor. Said lugs have tapped holes, into which are inserted the screws h' , having a turning nut or collar, h^2 , and pointed or otherwise suitably configured ends h^3 , which are 5 designed to engage with the helices F. By turning the screws h' their ends h^3 penetrate between the coils or helices F and lock the armature B firmly upon shaft A, so that the former will rotate with the latter. When it 10 is desired to remove the armature from said shaft, the screws h' are reversely turned, which disengages their ends h^3 from said helices, whereupon the armature is released from the shaft. While the ends h^3 of screws or arms h' 15 are shown tapered to a point, yet in practice they are so tapered that their extreme ends will be more or less rounding, and are designed to be covered with a non-conductor, so that when forced into or between the coils of the 20 armature-helices the insulation of the latter is not destroyed or the machine short-circuited; or said arms may be made of hard wood, gutta-percha, or other non-conducting material.

I I, Fig. 5, represent the pole-pieces of the 25 field-magnets. Said pole-pieces surround the armature in the usual or other suitable manner. Heretofore they have been formed in one piece or section. Consequently when the armature needed to be removed from the 30 machine, in order to repair its burned-out helices, or to otherwise manipulate it, the housings and other parts of the machine had first to be removed before access could be obtained to the armature. To avoid such disadvantage, I construct the pole-pieces in two sections, *i* *i'*, and 35 bolt or otherwise secure them together, as shown; hence, when the armature of my machine is designed to be taken therefrom, all that is necessary to do is to remove the upper 40 or one of the sections of each pole-piece and take off the upper bearing-plate of the shaft A, whereupon the latter and the armature may be lifted out of their normal position without disarranging the remaining parts of the 45 machine.

The blocks G G' may be formed or constructed in any suitable manner, so as to be readily inserted upon the ring D. In Fig. 3 I have illustrated them as being composed of 50 two sections, which when placed in position upon the armature are screwed or otherwise connected together, as shown. I have indicated the ring D provided with flanges b b , and prefer to use such construction, as the helix E may be then more readily coiled upon 55 ring D; but, if desired, said flanges may be dispensed with, as said helix E is held in place on said ring D by the transverse helices F. So, too, while I have shown and described the 60 use of the iron-wire helix E for the soft-iron core of the armature, and such core placed upon a veneering of wood or other non-conductor, I do not confine my invention thereto, as such helix and non-conductor may be dispensed with, and in lieu thereof the usual iron 65 ring, but having perforations, may be substi-

tuted therefor. Again, if desired, the hub or sleeve H may be dispensed with, and the screws h' inserted directly in the shaft A.

The ends of the helices F may be connected 70 to the commutator C in the usual or other desirable way, which need not be more particularly described, as the construction of the commutator or the mode of connecting the helices F thereto forms no part of my invention. 75

What I claim is—

1. An armature for dynamo-electric machines, composed of a core-piece, helices F F', and air-chambers G and G', the former having projecting sides or lips g^3 formed integral therewith, substantially as shown and described. 80

2. In an armature for dynamo-electric machines, the combination of frame or ring D, having perforations d' , air-chamber D', core E, helices F F', and air-chambers G and G', the former having projecting sides or vanes g^3 , substantially as shown and described. 85

3. The combination of a non-conducting frame or ring, D, having perforations d' , air-chamber D', uninsulated wire core E, helices 90 F F', chambers G, having closed tops, open bottoms, and vanes g^3 , and chambers G', having closed bottoms and open tops, substantially as shown and described.

4. An armature for electric generators, having a series of fan-blades, induction-openings leading to air-chambers located between the insulated helices and the core-piece, and the latter being perforated, and eduction-openings therefor, substantially as set forth. 95

5. In a dynamo-electric machine, an armature consisting of a loose wire core, a frame or support for said core, perforated or channeled for the purpose set forth, and helices wound around said core and support, substantially as 100 described.

6. An armature for electric generators, composed of a core having air-passages formed therein, a series of helices arranged transversely to said core, and interposed air-chambers between said core and helices, substantially as 105 shown and described.

7. An armature for electric generators, composed of a diamagnetic frame or ring, a core-piece provided with air chambers or passages, 115 helices therefor, a series of fan-blades, and an air-chamber between said helices and core-piece, substantially as shown and described.

8. An armature for electric generators, composed of a diamagnetic frame or ring, a core, 120 a series of helices, internal air-chambers between the core and helices, and air-forcing or blast-producing devices rotating with said armature, substantially as shown and described.

9. An armature for electric generators, composed of a core having air-passages, a series of helices, and an air-chamber between said core and helices, in combination with means attached to and rotating with the armature for forcing a current or currents of air through 125 said armature, as set forth.

10. An armature for electric generators, com-

posed of a cylinder of wood veneer or other non-conductor, provided with perforations, an iron helix wound on its exterior periphery, a series of transverse helices, an air-chamber 5 between the latter and the perforated non-conductor, and means for forcing a blast or blasts of air through said armature, substantially as set forth.

11. The combination of ring D, having perforations or openings d' , the rings d^t , the iron-wire helix E, helices F, and interposed hollow blocks G G', with projections g^s , substantially as shown and described.

12. The combination of ring D, having perforations d' , rings d^t , and flanges d, the iron-wire helix or core E, helices F, interposed hollow blocks G G', and projecting sides or blades g^s , substantially as shown and described.

13. In a dynamo-electric machine, the combination of an armature, a driving-shaft, and a field-of-force magnet whose pole-pieces are each composed of two uniting-sections, one of

which is removable from the other, as and for the purpose set forth.

14. In combination with an electric generator, a field-of-force magnet, the pole-pieces of which are each composed of a uniting fixed and a removable section, substantially as shown and described.

15. The pole-piece I, composed of two uniting-sections, i and i' , one of which is permanently secured to the field-of-force magnet, and the other is removable from said fixed section, substantially as shown and described.

16. In combination with an armature for electric generators, the blocks G', having internal air-passages and projecting blades or sides g^s , substantially as shown and described.

In testimony whereof I affix my signature in presence of two witnesses.

JAMES W. EASTON.
